DANCING TAP

Frank J. Du Mont and Dorothy H. Sargent, Philadelphia, Pa., assignors to Frank J. Du Mont, Dorothy H. Sargent, and Joseph E. Casper, doing business as Du Mont, Sargent and Casper, a copartnership

Application February 11, 1947, Serial No. 727,784

6 Claims. (Cl. 36—8.3)

1

The present application is a companion case of our co-pending application, Serial No. 678,494, filed June 21, 1946, relating to dancing taps. In the aforesaid application, there is disclosed a dancing tap comprising a base element, a freely floating sound producing element, and means for locking the sound producing element within the base element. More specifically, the base element may be provided with an overhanging side flange forming a groove, and the sound element may consist of a flat plate or disc with an extending flange that is freely held within the groove of the base. The base is provided with screw openings positioned under the disc for attaching the tap to the dancing shoe, and the component base and sound elements are locked together by means which may be attached either to the base or the sole of the pump.

The above-described dancing tap is characterized by the feature that all screws for attaching the tap to the dancing pump are concealed or held out of contact with the floor or other dancing surface, thereby avoiding marring said surface by the screws becoming loose and projecting beyond the outer surface of the base member. Further, the dancer is thus saved from embarrassment by having the screws become loosened and permitting the tap to become disengaged from the pump.

The present tap construction is an improvement over the dancing tap disclosed in our aforesaid companion application.

An object of the invention is the provision of a sturdy, durable dancing tap simple in construction and economical to manufacture.

Another object is the provision of a tap which gives the dancer at all times perfect balance.

Another object of the invention is to improve the sound effects of the tap, make it easy to tune, and more positive in operation.

Other objects relating to features of construction, combination of elements and arrangement of parts are either obvious or will manifest themselves as the description proceeds.

For a full and more complete understanding of the invention, reference may be had to the following description and accompanying drawings, wherein:

Figure 1 is a plan view, partly in section, of the bottom of a tap for the heel of a dancing shoe;

Figure 2 is a plan view, partly in section, of the tap heel member with the sound producing element removed;

2

Figure 3 is a sectional elevation illustrating the tap attached to the heel of the dancing shoe;

Figure 4 is a bottom plan view of the insert or floating sound producing element;

5 Figure 5 is a section of the sound element taken on line 5—5 of Figure 4;

Figure 6 is a sectional elevation of the tap for the toe of the shoe;

10 Figure 7 is a bottom plan view, partly in section, of the toe tap;

Figure 8 is a section on the line 8—8 of Figure 7;

15 Referring now to the drawings, wherein like reference characters denote corresponding parts, it will be noted that our dancing tap is designed to conform either to the general shape of the heel or the toe of the shoe, and that with respect to the several modifications disclosed, the two tap members, heel and toe, constitute a mated pair, 20 although either may be used separately at the choice or pleasure of the dancer.

25 Referring particularly to the modification shown in Figures 1 to 4, it will be seen that a tap embodying the present invention is essentially composed of a base member, designated generally by the reference character 1, and a sound producing element, indicated generally by the numeral 2, and means for locking the sound

30 producing element to the base member. The base member may comprise a metal frame 3 having a hollow central portion, with the perimeter of the frame following the general configuration of the part of the shoe to which the 35 base member is to be attached. That is to say, in the tap for the heel, the base member 1 comprising the frame 3 is substantially semielliptical in shape with the vertex 4 formed on a radius substantially coinciding with the curvature of the heel 5 of the shoe and the sides 6 and 7 of the frame being substantially complementary with the sides of the heel 5. In the case of the 40 tap for the toe, the frame 3 of the base member 1 is substantially shaped like an isosceles triangle with the apex 8 formed on a radius substantially coinciding with the curvature of the tip of the toe of the shoe with the sides 9 and 10 following the general contour of the sides 45 of the toe. The base or frame 3 of the tap for the toe may be slightly curved transversely on its inner plane surface, as shown in Figure 8, 50 whereby it conforms more closely to the contour of the shoe toe.

55 From the foregoing description, it will be ob-

served that the base member 1 may be regarded generally as a yoke closed at the bottom by a transverse arcuate shaped cross piece 11 forming a closed hollow frame which may be cast in one piece from some suitable light metal, such as aluminum.

The inner wall at the bottom edge of the frame 3 is provided with an inwardly extending flange which may constitute a ledge or seat 12 for the sound producing element 2. The seat 12 is provided with fastener openings such as countersunk holes 13 for the accommodation of head screws 14 which are adapted to engage the bottom surface of the shoe heel or toe (see Figures 3 and 6). By this arrangement, the tap may be firmly secured to either the heel or toe of the shoe, and, as will be noted, covers substantially the entire surface of said parts.

The sound producing element 2 comprises a relatively thin flat plate or disc 16, which is adapted to be inserted in the opening of the frame 3, and has a configuration conforming to the shape of the respective tap it is intended to be a component part; that is to say, the shape of the disc 16 for the toe tap is generally triangular and for the heel elliptical. The disc 16 is also provided with a taper corresponding to the taper of the base member 1, and the fit between the sound element 2 and the frame 3 is such that the element 2 freely floats within the base member 1, with the edge or perimeter of the former in seating engagement with the flange 12.

The inner or forward portion of the disc 16 is provided with a tongue 17 adapted to overlap and register with a supporting shoulder 18, said tongue and shoulder constituting an interlocking hinge arrangement for pivotally mounting the rear end of the disc 16 on the base 1. The outer or rear end of the base 2 is provided with a threaded recess 19 adapted to receive a set screw 20. The end of the set screw 20 is turned down to form a shank portion which is adapted to fit loosely in an aligned opening 21 formed in the disc 16. By manipulating the set screw 20, the disc 16 may be adjusted on the base 1.

This adjustment affords means for tuning the tap for sound effects, i. e., the closer the setting of the screw 20, the tighter will the disc 16 fit within the frame, and vice versa, the farther away said screw is set, the more loosely the disc 16 is held. It is, therefore, apparent that the sound producing effect is materially dependent upon the degree of float given the disc 16, which in turn is governed by the adjustment of the set screw 20, and that this adjustment may vary the sound effects for a considerable range between zero and the maximum volume. It will also be noted that the fastening screws 14 are juxtaposed with respect to the outer edge or perimeter of the disc 16, and the seat 12 on the frame 3, so that if any of the screws 14 become loosened through dancing, they can not become dislodged because they are completely covered by the edge of the disc 16, which disc is retained within the frame 3 by the above described auxiliary or independent fastening means consisting of the hinge construction at one end and the set screw 20 at the other end.

It may be pointed out here that the depth of the seat 12 from the outer surface of the base member 1 is appreciably greater than the thickness of the disc 16 so that said disc is normally spaced away from the seat 12, through the action of gravity, when the tap is lifted or removed

from the dance floor during the dancing performance. This feature is illustrated particularly in Figure 3. It will, of course, be understood that this vertical movement or play given to the disc 16 within the frame 3 is such that at no time will the disc extend or project beyond the bottom surface of the frame 3; also that no adjustment for sound effects is necessary or contemplated by the adjustment of the head screws 14, which is a feature of the tap construction disclosed in my aforesaid companion application, Serial No. 678,494. Therefore, the screws 14 may be drawn tightly, thus further avoiding the possibility of the tap becoming loose on the dancing shoe, to the embarrassment of the dancer.

The sound producing element 2 may be provided with a sound chamber 22 consisting of a cavity either formed during the casting of the disc 16 or by machining the same after casting. The shape and/or size of the cavity may be empirical depending upon the quality and/or volume of resounding effect it is desired to produce. The principal function of the sound chamber 22 is, of course, to amplify and/or roughly modulate the sound of the disc 16 striking against the seat 12 when the foot of the dancer contacts the floor.

While certain preferred specific embodiments of the invention are herein set forth, it is to be clearly understood that the invention is not to be limited to the exact constructions described and illustrated because further modifications as to details and arrangement of parts may be made in putting the invention into practice, and it is intended to cover all such modifications as come within the scope of the appended claims.

What is claimed is:

1. In a tap for dancing shoes and the like, an open metal frame base member substantially conforming to the outline of a portion of the bottom of a shoe, an inwardly extending marginal flange formed contiguous with the inner edge of the base frame, said flange constituting a depressed seat provided with screw openings for fastening the tap to the shoe; a sound producing element freely suspended within the frame of said base member and covering the fastening screws; means for locking said sound producing element to the base member, said locking means comprising a tongue projecting from one end of said sound producing element which is adapted to engage a complementary shaped shoulder formed on the inner end of the base member, and a pivotal arrangement consisting of a set screw mounted in the outer edge of the base member and adapted to engage an aperture formed in the sound producing element, whereby in manipulating said set screw an adjustment may be obtained in the suspension of the sound element.

2. In a construction for a dancing tap, an open metal frame base member, said base member comprising a yoke piece having a closed rounded end portion with arms extending laterally therefrom, the open ends of the arms being closed by a strap-like cross piece having an inwardly extending shoulder portion, an inwardly extending flange formed adjacent the inner vertical wall of said base member, said flange being provided with fastener openings; a sound producing element freely suspended within the frame of said base member, said sound element comprising a disc having a sound amplifying chamber; and means for adjustably attaching said sound element to the base frame, said attaching means comprising a tongue portion and a cavity formed on the opposite ends of the sound element, the

tongue portion being adapted to engage a shoulder formed transversely of the base member and a set screw adapted to register with said cavity, whereby the sound element is freely pivoted between said pivotal points and adapted to strike said flange portion when the tap comes in contact with a floor surface or the like.

3. In a tap for dancing shoes and the like, an open metal frame base member adapted to be applied to the bottom of a shoe, and an inwardly extending marginal flange formed contiguous with the inner edge of the base frame, said flange constituting a depressed seat provided with screw openings for fastening the tap to the shoe, a sound producing element freely suspended within the frame of said base member and covering the fastening screws, a set screw for locking said sound producing element within the frame of said base member and adapted to engage said sound producing element, whereby in manipulating said set screw an adjustment may be obtained in the suspension of the sound element.

4. In a tap for dancing shoes and the like, an open metal frame base member substantially conforming to the outline of the heel of a shoe, and an inwardly extending marginal flange formed contiguous with the inner edge of the base frame, said flange constituting a depressed seat provided with screw openings for fastening the tap to the shoe, a sound producing element freely suspended within the frame of said base member and covering the fastening screws, a tongue projecting from one end of said sound producing element adapted to engage a complementary shaped shoulder formed on the inner end of the base member, and a set screw mounted in the outside edge of said base member and adapted to engage said sound producing element, whereby in manipulating said set screw an adjustment may be obtained in the suspension of the sound element.

5. In a tap for dancing shoes and the like, an open metal frame base member substantially con-

forming to the outline of the toe of a shoe, and an inwardly extending marginal flange formed contiguous with the inner edge of the base frame, said flange constituting a depressed seat provided with screw openings for fastening the tap to the shoe, a sound producing element freely suspended within the frame of said base member and covering the fastening screws, a tongue projecting from one end of said sound producing element adapted to engage a complementary shaped shoulder formed on the inner end of the base member, and a set screw mounted in the outside edge of said base member and adapted to engage said sound producing element, whereby in manipulating said set screw an adjustment may be obtained in the suspension of the sound element.

6. In a tap for dancing shoes and the like, an open metal frame base member adapted to be applied to the bottom of a shoe, and an inwardly extending marginal flange formed contiguous with the inner edge of the base frame, said flange constituting a depressed seat provided with screw openings for fastening the tap to the shoe, a sound producing element freely suspended within the frame of said base member and covering the fastening screws, means for locking said sound producing element within the frame of said base member, and an adjusting means in said base member adapted to engage said sound producing element, whereby an adjustment may be obtained in the suspension of the sound element.
